RADIO TUNING SYSTEM

Vernon D. Landon, Haddonfield, N. J., assignor to
 Radio Corporation of America, a corporation of
 Delaware

Application January 2, 1940, Serial No. 312,072

7 Claims. (Cl. 250—40)

The present invention relates to radio tuning systems, and has for its primary object to provide an improved tuning system of the character referred to wherein two variably tunable circuits having magnetic core variable inductances are caused to track over a predetermined tuning range.

It is also an object of the present invention to provide a superheterodyne oscillator tracking system embodying magnetic core tuning whereby alignment between the oscillator and R.-F. circuits is maintained over a mid-frequency portion of the tuning range as well as at the ends of said range.

It is a still further object of the invention to provide a superheterodyne oscillator tracking system embodying magnetic core variable tuning for covering a plurality of tuning range with the same tuning inductances.

The invention will, however, be better understood from the following description when considered in connection with the accompanying drawing, and its scope is pointed out in the appended claims.

In the drawing,

Figure 1 is a schematic circuit diagram of a tuning system embodying the invention, and

Figure 2 is a similar schematic circuit diagram showing a modification of a portion of the circuit of Fig. 1, also embodying the invention.

Referring to Fig. 1, 5 is a tuning inductance of the solenoid type for the antenna or R.-F. stage of a superheterodyne receiver and 6 is a similar oscillator tuning inductance arranged to be tunable conjointly with the first named inductance over a predetermined variable tuning range or a plurality of such ranges by means including a movable magnetic core 7 in the R.-F. stage inductance and a movable magnetic core 8 in the oscillator tuning inductance joined or connected as indicated by the dotted connection 9, in a manner to move jointly in unison. Additional means hereinafter referred to, such as shunt capacitors for the inductances, further determine the ranges of the inductances 5 and 6.

With magnetic core tuning, as with other forms of variable tuning, the problem in tracking two or more variable tuning circuits involves the lining up or frequency adjustment of the circuits at not only the high and low frequency ends of the tuning range, but also at one or more intermediate points between the ends of the tuning range. Furthermore, as in a superheterodyne receiver, the tuning of the two or more circuits by unitary control means involves

covering differing frequency ranges in the several circuits. Thus, the oscillator may have a lower ratio of frequency ranges to cover than the R.-F. stage and in order to track properly a tuning system may require the use of means for modifying the rate of change of inductance in one or the other of two or more simultaneously variable tuning circuits.

For example, where two variable tuning ranges are provided between two circuits, such as the R.-F. and oscillator circuits of a superheterodyne receiver covering a lower band of frequencies and a higher band of frequencies, such as the normal broadcast and short wave bands, it has been found that the circuits may be made to track effectively over the high frequency range with an oscillator inductance coil only slightly greater in diameter than the R.-F. coil, and over the low frequency range by utilizing an oscillator tuning inductance of considerably larger diameter than the R.-F. tuning inductance. Also the tracking in the mid-tuning portion of the range is corrected if a portion of the oscillator coil, preferably at the entering end of the coil, with regard to the core, is shunted by a capacitor, the value of which is adjusted to bring the tracking of the two circuits into alignment in that portion of the variable tuning range.

If desired the diameters of the two coils may be made the same and a small fixed inductance may be inserted in series with the oscillator inductance. The added series inductance produces about the same effect in shortening the oscillator tuning range than an increase in oscillator coil diameter would have produced.

In Fig. 1, the oscillator coil 6 is only slightly larger in diameter than the R.-F. coil 5, so as to track over a high frequency range. When larger shunt condensers are used so as to cover a lower frequency range, a further decrease in oscillator tuning range is required. Since the diameter cannot be changed, having been fixed by the requirements of the high frequency range, the required reduction in range is accomplished by inserting a series inductance as shown and described hereinafter.

In the circuit of Fig. 1, the inductances 5 and 6 are provided with suitable capacitors and switching means whereby they may be adjusted for tuning through the high and low frequency ranges referred to, also as hereinafter pointed out, and are connected in circuit with a mixer or converter tube 10 having a signal input grid 11 connected to the high potential terminal 12 of the R.-F. inductance 5 and an oscillator grid 13

connected with the high potential terminal 14 of the oscillator inductance 6 through the usual grid leak and capacitor 15.

The entering end of the inductance 5 for the core 7, which is the low potential end of the inductance, is provided with a terminal 16 connected to ground or chassis 17 as is also a corresponding terminal 18 on the inductance 14.

For the high frequency tuning range, the R.-F. or antenna circuit is provided with a shunt capacitor 20 and a series capacitor 21 in circuit with an antenna or signal collector 22. Connections with the capacitors 20 and 21 are provided by switches 23 and 24 arranged to be operated conjointly, as indicated by the dotted connection 25. Each of the switches is provided with an alternative connection whereby, for the low frequency tuning range, a capacitor 25 of higher value is placed in series with the antenna and a capacitor 26 also of higher value is placed in shunt with the inductance 5 to add capacity for the lower tuning range as provided by the movable core 7.

In the oscillator circuit, which is of the Colpitts type by way of example, a pair of series connected capacitors 27 and 28 across the inductance 6 provide a tap connection 29 for the oscillator cathode 30 and, in addition, provide for tuning the oscillator circuit at the high frequency end of the tuning range. Movement of the core 8 into the coil 6 lowers the frequency response of the oscillator circuit.

To simplify manufacture and reduce cost, it is preferable that similar cores of high permeability be used in coils which are of substantially equal length and diameter. With this arrangement, however, it has been found that the oscillator may cover too great a frequency range and may be lined up for tracking at only one frequency with the R.-F. stage. Referring to both Figs. 1 and 2, wherein like reference numerals are used for the same parts and circuits as in Fig. 1, if the oscillator coil diameter is increased to a suitable value, while maintaining the R.-F. or first circuit the same, a desired wide tuning range may be covered, but the oscillator may become too high in frequency and thus out of alignment in the mid-portion of the tuning range.

It has been found, however, that proper alignment for tracking may be had in the mid-portion of the tuning range by tapping one of the coils or inductances, such as the oscillator inductance, at substantially one-third of its length from the high frequency end, that is, the entering end, and connecting a capacitor in shunt with the coil between said tap and said end. In Figs. 1 and 2, the tap is indicated at 32 and the capacitor is indicated at 33, connected between the tap 32 and the terminal 18 across the lower portion of the inductance 6. The capacitor 33 is adjusted to a value such that alignment of the two circuits is provided at the mid-tuning range, thereby completing the alignment of the circuits for high and low frequency tuning with the same coils. In other words, for tuning through the high frequency range such as the short wave broadcast range the two inductances 5 and 6 may be of the same length and only slightly different diameter, with the same core material and size of core as for tuning through the low frequency range. The oscillator inductance in the present case or the inductance of the circuit having the lower tuning range is increased in diameter as indicated at 6a, Fig. 2, sufficiently to change the rate

of tuning variation to that which is proper for maintaining the circuits in alignment with uni-control movement of the several cores.

The diameter of the winding 6a in Fig. 2 is determined by the shape and length of the core 8 which may be the same as in Fig. 1. In any case, the diameter of the two windings 5 and 6a differ by an amount sufficient to provide tracking between the two tuned circuits when simultaneously tuned by magnetic or other suitable movable cores which are moved by uni-control means.

As hereinbefore referred to, if the oscillator coil diameter is increased to a predetermined value, the desired tuning range will be provided by the oscillator, with the oscillator frequency slightly high in the mid-tuning range to produce a predetermined intermediate frequency. This is corrected by the shunt capacitor 33 across a portion of the winding at the entering end of the winding, which as used herein refers to the end of the winding which the core enters and leaves in tuning.

When a second tuning range at the lower frequency is desired, the windings 5 and 6 of Fig. 1 and the winding 6a in Fig. 2, may be shunted by additional capacitors or capacitors of higher or lower values to produce a second tuning range at a lower mean frequency. These are provided in the present example by the capacitors 25 and 26 across the R.-F. coil 5 and by capacitors 35 and 36 connectable across the capacitors 27 and 28 in the oscillator circuit by a switch 37 when moved to the alternate position from that shown in the drawing, closing contacts 38 and 39 with a lead connection 40 for the cathode circuit 41 of the oscillator tube 10.

At the same time a switch 42 operable jointly with the switch 37 serves to connect an additional capacitor 43 in parallel with the capacitor 33 across the tapped portion of the oscillator coil thereby to correct the tuning and alignment of the oscillator with the R.-F. circuit in the mid-range of the low frequency tuning band.

It will be noted that an inductance 44 is included in Fig. 1 in series with the capacitor 35 in shunt with the capacitor 27.

The switching arrangement of Fig. 1 adapts the tuning system for receiving signals in a high frequency range, such as the short wave band and in a second lower frequency range, such as the present broadcast band, by increasing the values of the shunting capacitors of the oscillator and R.-F. circuits and by inserting a small inductance in series with the oscillator coil which approximately permits tracking in substantially the same manner as with a tuning inductance in the oscillator of greatly increased diameter which would otherwise be required to provide proper tracking between the two circuits in the lower frequency band.

In one embodiment of the invention, the tuning range was changed by increasing the tuning capacitors approximately 10 to 1. In the oscillator of the present example, the capacity at 27 from grid to cathode, the capacity at 28 from cathode to ground, and the capacity at 33 from the tap to ground are increased by the addition of capacitors 35, 36 and 43, respectively.

The additional cathode to ground capacitor 36 is adjusted for optimum oscillator operation by providing the proper feedback. The additional capacitor 35 from grid to cathode chiefly affects the tuning range, and the capacitor 43 on the tap connection is adjusted to a value resulting in best tracking in the mid-range of the low

frequency tuning band. The series inductance 44 is in series with the grid-cathode capacitor 35 and makes it unnecessary to change the diameter of the oscillator coil for the lower frequency tuning band while securing good tracking throughout the tuning range of the oscillator.

It has been found that the rate of change of frequency with core movement varies rapidly as the coil is just entering the coil or winding and also when the core is substantially completely in the coil. With tuning inductance or coils of different diameters in the several circuits, such as the R.-F. and oscillator circuits, as hereinbefore referred to, the variation in frequency differs and tracking in the extreme limitation of a tuning range in any band of frequency may be improved by a slight shortening of the length of one of the coils and a slight axial shift in position.

While the invention has been described in connection with the variable R.-F. and oscillator tuned circuits of a superheterodyne receiver as the present preferred embodiment of the invention, it should be understood that the invention is not limited thereto but may be applied to other magnetic core tuning circuits with unitary or conjoint control of the tuning.

In any case, however, the rate of change of frequency at the entering end of the tuning inductance of any of the uni-controlled circuits may be increased or changed by tapping the inductance winding in spaced relation to the entering end and connecting a capacitor of a predetermined value between the tap and the said end of the winding, and the tracking of any two circuits may be improved by increasing the diameter of one of the variable inductance windings in the tuning circuits while utilizing substantially the same cores, that is of the same material and shape in each of the two windings for lower cost of production.

The cathode of the oscillator is connected to ground 17 through an inductance winding 47 and a cathode resistor 48 for the purpose of providing a high impedance path to ground for R.-F. currents while maintaining the D.-C. impedance that of the cathode resistor. This, however, forms no part of the present invention. Likewise, the output circuit of the oscillator comprising the anode 49 and the intermediate output transformer 50 is conventional and requires no further description.

I claim as my invention:

1. In a radio tuning system, the combination of two tunable signal circuits each comprising an inductance winding, similar magnetic tuning cores for said windings adapted to enter one end of each winding and to move therethrough, thereby to provide variable tuning of said circuits, uni-control means for moving said cores conjointly in predetermined relation to each other, thereby to cause tracking in the tuning of said circuits, and a capacitor connected in shunt with a portion of at least one of said windings adjacent the entering end thereof with respect to the core movement to improve the tracking of said circuits in a predetermined portion of the tuning range of said system.

2. In a radio tuning system, the combination of two tunable signal circuits each comprising an inductance winding, means providing a shunt capacity across each of said windings for tuning said circuits each to a predetermined frequency, similar magnetic tuning cores for said windings adapted to enter one end of each winding and

to move therethrough, uni-control means for moving said cores conjointly, and means providing capacity in shunt with a portion of at least one of said windings adjacent the entering end thereof with respect to core movement for causing improved tracking of said circuits in a mid-frequency range, one of said windings being of a larger diameter than the other for further improving the tracking of said circuits throughout a predetermined frequency range including said mid-frequency range.

3. In a radio tuning system, the combination of two tunable signal circuits each comprising an inductance winding, means providing a shunt capacity across each of said windings for tuning said circuits each to a predetermined frequency, similar magnetic tuning cores for said windings adapted to enter one end of each winding and to move therethrough, one of said coils being displaced with respect to the entering end of the core associated therewith, uni-control means for moving said cores conjointly into and through at least a portion of said coils, means providing capacity in shunt with a portion of at least one of said windings adjacent the entering end thereof with respect to core movement for causing improved tracking of said circuits in a mid-frequency range, one of said windings being of a larger diameter than the other for further improving the tracking of said circuits throughout a predetermined frequency range including said mid-frequency range.

4. In a superheterodyne receiver, the combination with a tunable signal circuit having a tuning inductance comprising a solenoid coil provided with a movable magnetic core tuning element, of an oscillator circuit comprising a second tuning inductance comprising a second solenoid coil of larger diameter than said first coil, a second like movable magnetic core tuning element for said last named inductance adapted to enter one end of the said inductance in the tuning movement of the core element, and a capacitor connected in shunt with a portion of the second tuning inductance adjacent to said end.

5. In a superheterodyne receiver, the combination with a tunable signal circuit having a tuning inductance provided with a movable magnetic core tuning element, of an oscillator circuit comprising a second tuning inductance, a second like movable magnetic core tuning element for said last named inductance adapted to enter one end of the said inductance in the tuning movement of the core element, means providing a capacity connected in shunt with a portion of the second tuning inductance adjacent to said end, for tracking said circuits in a predetermined portion of the tuning range thereof.

6. In a radio tuning system, the combination of two tunable signal circuits each comprising a tuning inductance provided by a solenoid coil, one of said coils being of larger diameter than the other, similar magnetic core tuning elements for said coils adapted to be moved conjointly and to enter one end of each winding, thereby to vary the tuning of said circuits through predetermined frequency ranges, the difference in diameter of said coils providing for tracking said circuits over the tuning range thereof with a predetermined uniform frequency difference, and a capacitor connected in shunt with a portion of the coil of larger diameter adjacent the entering end thereof, said capacitor having a value

such that the tracking of said circuits in a mid-portion of the tuning range is caused to conform with the tracking of said circuits throughout the remainder of the tuning range thereof.

7. In a superheterodyne receiver, the combination with a tunable signal circuit having a tuning inductance of the solenoid type provided with a movable magnetic core tuning element, of an oscillator circuit comprising a second tuning inductance of the solenoid type, a second-like movable magnetic core tuning element for said last-named inductance adapted to enter one end of the said inductance in the tuning

movement of the core element, means providing a capacity connected in shunt with a portion of the second tuning inductance adjacent to said end, means providing a tuning capacity for each 5 of said inductances connected in shunt therewith, a third tuning inductance, and means for simultaneously increasing the value of said last-named capacities and said first-named capacity and inserting said third tuning inductance in 10 series with said second tuning inductance, thereby to change the tuning range of said circuits by a predetermined amount.

VERNON D. LANDON.
